UNITED STATES PATENT OFFICE.

CHARLES E. HYATT, OF EAST ORANGE, NEW JERSEY, ASSIGNOR TO THE CUTLER-HAMMER MFG. CO., OF MILWAUKEE, WISCONSIN, A CORPORATION OF WISCONSIN.

MOTOR-CONTROLLER.

1,102,337.

Specification of Letters Patent. Patented July 7, 1914.

Application filed November 12, 1910. Serial No. 581,951.

To all whom it may concern:

Be it known that I, CHARLES E. HYATT, a citizen of the United States, residing at East Orange, in the county of Essex and State of New Jersey, have invented new and useful Improvements in Motor-Controllers, of which the following is a full, clear, concise, and exact description, reference being had to the accompanying drawing, forming a part of this specification.

My invention relates to improvements in motor controllers. More particularly my invention relates to controllers for slowing down electric motors, prior to stopping the same.

In practice there are many instances where it is extremely desirable, and in fact a requirement, to bring the load operated by the motor to rest in a certain position or positions with a fine degree of accuracy. To do this requires slow down of the motor, prior to stopping the same. Furthermore, the desired slow down of the motor must ordinarily be accomplished within a predetermined period of time. Where a motor always operates under the same load it is a simple matter to regulate the slow down to accurately bring the load to a standstill at the desired point or points and within the given period of time. Where, however, the load is variable the problem is much more difficult.

One object of my invention is to provide a simple and efficient controller which will insure accurate stopping of the motor and always within a given period of time whether the load under which it operates be constant or variable.

My invention also has various other objects and advantages which will hereinafter be clearly and fully set forth.

In order to clearly and fully disclose the nature and advantages of my invention, I shall describe the controller diagrammatically illustrated in the accompanying drawing, which embodies my invention in one form.

Of course my invention is susceptible of embodiment in various other forms, the controller illustrated in the accompanying drawing merely serving for the purpose of illustration.

In the drawing is shown a motor 1 having an armature A and a shunt field wind-

ing F. In series with the motor armature is a variable starting resistance R connected to a series of contacts 2. A pivoted arm 3 having a contact brush 4 adapted to sweep over said contacts 2 is provided for controlling said resistance R. The arm 3 is also provided with additional contact brushes 5, 6, 7, 8 and 9. The contact brushes 5, 6 and 7 are electrically connected to one another but are insulated from the arm 3. Contact brushes 8 and 9, on the other hand, are both electrically connected to the arm 3. The contact brush 4 in addition to engaging contacts 2 is adapted to be moved over a contact segment 4^a electrically connected to the contacts 2. Contact brushes 5, 6, 7, 8 and 9 are adapted to be moved over contact segments 5^a, 6^a, 7^a, 8^a and 9^a, respectively for the establishment of the circuits hereinafter described. Resistances r, r' and r² are adapted to be connected in shunt with the motor armature by an electroresponsive switch 10 under the conditions and for the purpose hereinafter set forth. For controlling the resistances r to r², after the same have been connected in shunt with the motor armature, are provided electroresponsive switches 11, 12 and 13 adapted to operate under the conditions and with the results hereinafter set forth.

I shall now describe the operation of the controller at the same time clearly setting forth the various circuit connections and the functions of the various parts. It may be assumed that the motor is employed for raising a load which may vary within predetermined limits. Assuming the arm 3 to be in the position illustrated, the motor circuit will be open and the motor at rest. Of course, in practice where a motor is employed for hoisting purposes, a mechanical brake is ordinarily provided to hold the motor against movement after the same has come to rest. The motor may be started by moving the arm 3 to the right to bring contact brush 4 into engagement with contact segment 4^a. Assuming that current is supplied to the motor from supply lines 16 and 17, circuit will now be closed from supply line 16 through the arm 3 and contact brush 4 to contact segment 4^a; thence through the resistance R by conductor 18 through the motor armature to supply line

17. The shunt field winding F being permanently connected across the supply lines, as illustrated, the motor will immediately begin to operate. Under these conditions, 5 however, the motor will only operate at a slow speed, owing to the insertion of the resistance R in its armature circuit. Upon continued movement of the arm 3 to the right, the contact brush 4 will pass over the 10 contacts 2, gradually removing the resistance R until the motor has been brought up to normal speed.

Let it now be assumed that when the motor has operated to bring the load within a predetermined distance of the point at which it is to be stopped, the arm 3 is automatically moved in synchronism with the motor or load operated thereby, in an opposite direction to that just described. Movement of 15 the arm 3 in this direction reinserts the resistance R which slows down the motor. Of course the slow down effect of the resistance R is limited and is at its maximum when that arm 3 reaches contact segment 4^a. Continued automatic movement of the arm 3, 20 however, brings the same into engagement with segment 9^a. This completes a circuit from supply lines 16 through arm 3 and contact brush 9 to segment 9^a by conductor 25 20 through the operating winding of switch 10 to conductor 21 and thence to supply line 17. Switch 10 thereupon responds, connecting the resistances r , r' and r^2 directly across the terminals of the motor armature. The 30 establishment of this shunt circuit, as is well understood by those skilled in the art, further slows down the motor to a degree dependent upon the value of the resistance included therein, while the speed of the motor 35 may be still further decreased by decreasing said resistance. It is also understood that the establishment of the shunt circuit above described will have a greater slow down effect upon the motor when raising a 40 heavy load than when raising a light load, the converse being true when the load is lowered. Accordingly, when the motor is operating under a light load in hoisting and under a heavy load in lowering, more 45 resistance must be removed from the shunt circuit to obtain the desired speed reduction, than when converse conditions prevail. To meet these conditions, I have made provision, whereby when the arm 3 is moved to 50 the next slow down position, contact brushes 5 and 6 will bridge contact segments 5^a and 6^a. This results in connecting the operating winding of switch 13 across the terminals of the motor armature and therefore rendering the same responsive to the counter electromotive force of the motor armature. The circuit thus established may be traced 55 from the left hand terminal of the motor armature by conductors 18, 22 and 23 to contact segment 5^a, thence to contact seg-

ment 6^a by conductor 24 through resistance 25 and through the operating winding of switch 13 by conductor 26 and 27 to conductor 21 and thence to the right hand terminal of the motor armature. With these 60 connections, if upon establishment of the shunt circuit described the speed of the motor is not decreased to the desired degree owing to its having a light load when raised or a heavy load when descending, the 65 counter electromotive force of the motor armature will be sufficient to cause said switch 13 to respond. Switch 13 short circuits a portion of the resistance r^2 . Provision of the resistance 25 in series with the 70 operating winding of switch 13 prevents response of the switch 13, except when the counter electromotive force of the motor armature is at a predetermined minimum. Accordingly, said switch may be so regulated by said resistance as not to respond, except under predetermined conditions and by variation of said resistance, said switch 75 may be caused to respond at any predetermined counter electromotive force of the motor armature. The closure of switch 13 does not immediately reduce the speed of 80 the motor to the desired degree but as hereinafter described subsequently accomplishes this result. At the same time that the operating winding of switch 13 is connected across the terminals of the motor armature, contact brush 8 engages contact segment 8^a, completing a circuit from arm 3 by conductor 28 through the operating winding of 85 switch 11 to conductor 27. Thereupon switch 11 responds, short circuiting the resistance r . This, of course, tends to slow down the motor still further. When the arm 3 is moved still further to cause contact 90 brush 7 to engage contact segment 7^a, the operating winding of switch 12 is connected in parallel to the operating winding of switch 13 across the terminals of the motor armature. This switch, like switch 13 is 95 therefore responsive to the counter electromotive force of the motor armature, but unlike switch 13 it is designed to respond regardless of the load on the motor. In fact, it might be connected in parallel to the operating windings of switches 10 and 11, and therefore not be dependent upon the counter 100 electromotive force of the motor armature for its energization. Switch 12 in closing short circuits resistance r' . This, of course, 105 tends to still further reduce the speed of the motor.

Assuming now that the load on the motor is within predetermined limits and the switch 13 has not responded, the removal of 110 the resistances r and r' from the shunt slow down circuit will cause a sufficient reduction in the speed of the motor to insure accurate stopping of the motor when its circuit is 115 opened. Under these conditions all of the 120 125 130

resistance r^2 would remain in the shunt circuit. Should, however, the load on the motor not come within the predetermined limits, then as before set forth the switch 13 would respond practically simultaneously with the switch 11. This would short circuit a portion of the resistance r^2 . Thus closure of the switch 13 augments the effectiveness of the switches 11 and 12 and 10 determines the amount of resistance left in the shunt slow down circuit and by changing the point of connection between the switch 13 and the resistance r^2 any predetermined amount of resistance may be permanently included in said shunt circuit. Accordingly 15 the provision of the switch 13 enables automatic regulation of the slow down effect of the shunt circuit in accordance with the load under which the motor operates and further 20 facilitates regulation of this automatic control in accordance with the particular conditions to be met with. That is to say, the switch 13 may be adjusted to leave more or less resistance permanently connected in the 25 shunt circuit in accordance with the degree of variation of the load from the average.

It will be observed that the switch 13 if it responds does so within the period allowed for the successive operation of the switches 30 10, 11 and 12. In other words, all four switches will respond within the same period under conditions of variable load as is allowed for operation of three of the same under conditions of constant load. Therefore 35 with the arrangement illustrated no additional time is required for meeting and compensating for the conditions of variable load.

It should be understood that the controller 40 herein illustrated and described has been reduced to a very simple form in order to facilitate a clear understanding thereof. Of course, in practice, various additional features are commonly incorporated in such a controller, but it has been considered unnecessary to illustrate the same. In practice, the arm 3, or its equivalent is preferably operated either directly or through suitable means by the motor or the load 45 operated thereby and in synchronism therewith. Also, in practice, means may be provided for reversing the motor, and the same or separate slow down means may be employed for controlling the motor under conditions of reversal.

Various other additional features and refinements which are commonly used in practice might be herein set forth, but this is believed to be unnecessary.

Having thus described my invention what I claim as new and desire to secure by Letters Patent, is:

1. A motor controller comprising means operable to electrically slow down the motor, and means automatically responsive under

certain load conditions to vary the electrical effect produced by said first mentioned means at the time of its operation.

2. In a controller for electric motors in combination, means for slowing down the motor, and automatic means operating independently of said first mentioned means under predetermined load conditions to augment the slow down effect on the motor, said second mentioned means operating if at all prior to full operation of said first mentioned means.

3. In a controller for electric motors, in combination, means operable to gradually slow down the motor electrically and means adapted to operate automatically during the operation of said first mentioned means under predetermined load conditions to augment the slow down effect upon the motor.

4. In a controller for electric motors, in combination, means operable to gradually slow down the motor and means adapted to operate automatically during the operation of said first mentioned means under predetermined load conditions to augment the slow down effect upon the motor, said first mentioned means being operable to its full extent without operation of said second mentioned means under predetermined load conditions.

5. In a controller for electric motors, in combination, means operable to gradually slow down the motor, and means responsive under predetermined load conditions to operate with said first mentioned means to increase the slow down effect on the motor, said second mentioned means operating only upon a failure of said first mentioned means to slow down the motor to the desired degree upon a predetermined operation thereof and operating if at all prior to full operation of said first mentioned means.

6. In a controller for electric motors, in combination, a plurality of devices operable to slow down the motor, an auxiliary slow down device operating automatically under predetermined conditions to augment the slow down effect on the motor, all of said first mentioned devices being operable without operation of said auxiliary device, but said auxiliary device operating if at all during the operation of said first mentioned devices.

7. In a controller for electric motors in combination, a plurality of successively operated slow down devices for the motor, an auxiliary slow down device operating only when the combined effect of all of said first mentioned devices is inadequate to slow down the motor to the desired degree, but operating if at all prior to the operation of the last of said first mentioned devices.

8. In a controller for electric motors in combination, a plurality of slow down de-

- 5 vices, an auxiliary slow down device operating automatically under predetermined load conditions to augment the slow down effect of said first mentioned devices, said auxiliary device operating if at all during the operation of said first mentioned devices but not until after a predetermined number of said first mentioned devices have been operated.
- 10 9. In a controller for electric motors, in combination, means operated independently of the load conditions to slow down the motor and automatic means responsive to variations in the load conditions for varying the slow down effect of said first mentioned means, said second mentioned means operating if at all during the operation of said first mentioned means.
- 15 10. In a controller for electric motors, in combination, a plurality of slow down switches, a separate automatic slow down switch directly responsive to the load conditions and operating only when the combined slow down effect of the remaining switches is insufficient to slow down the motor to the desired degree, said automatic switch operating if at all during the operation of the remaining switches.
- 20 11. In a controller for electric motors, in combination, a plurality of slow down switches, a separate automatic slow down switch directly responsive to the load conditions and operating only when the combined slow down effect of the remaining switches is insufficient to slow down the motor to the desired degree, said automatic switch operating if at all during the operation of the remaining switches, and means for positively preventing operation of said automatic switch until a predetermined number of the remaining switches have been operated.
- 25 12. In a controller for electric motors, in combination, means for gradually slowing down the motor and means rendered responsive to the counter electromotive force of the motor armature prior to the full operation of said first mentioned means, to augment the effectiveness of said first mentioned means upon variations in the load on the motor.
- 30 13. In a controller for electric motors, in combination, a plurality of successively operated slow down switches, an auxiliary slow down switch responsive to the counter electromotive force of the motor armature and adapted to operate prior to the operation of the last of said first mentioned switches upon variations in the load on the motor.
- 35 14. In a controller for electric motors, in combination, a variable resistance connected in shunt with the motor armature, means for gradually removing a predetermined amount of said resistance to slow down the motor and means operating automatically upon variations in the load imposed upon the motor and prior to the full operation of said first mentioned means, to vary the resistance not controllable by said first mentioned means.
- 40 15. In a controller for electric motors, in combination, a variable resistance connected in shunt with the motor armature, means for gradually removing a predetermined amount of said resistance to slow down the motor and means operating automatically upon variations in the load imposed upon the motor and prior to the full operation of said first mentioned means to vary the resistance not controllable by said first mentioned means, said second mentioned means being responsive to the counter electromotive force of the motor armature.
- 45 16. In a controller for electric motors, in combination, a variable resistance connected in shunt with the motor armature, a plurality of successively actuated switches for short circuiting portions of said resistance to slow down the motor, a switch adapted to vary that portion of said resistance not controllable by said first mentioned switches, said second mentioned switches having an operating winding connected across the terminals of the motor armature and responding, if at all, prior to the operation of one of said first mentioned switches.
- 50 In witness whereof, I have hereunto subscribed my name in the presence of two witnesses.
